UNITED STATES PATENT OFFICE.

HENRY D. OBERDORFER, OF CHAMPAIGN, ILLINOIS.

CLOTHESRACK.

Application filed May 7, 1923. Serial No. 637,155.

This invention relates to clothes racks and more particularly to a knock-down clothes rack of the type commonly used for hotels, clubs, and the like, for the temporary disposal of wearing apparel of the guests. It may also be used permanently if desired. The principal object of the invention is to provide a clothes rack of this kind which can be easily and quickly assembled or knocked down, in which the parts are interchangeable with corresponding parts of similar racks, and to provide a simple, strong and compactly folding rack which can be made ready for use upon short notice without the necessity of tools of any kind in its assembling. Other objects will appear hereinafter.

In the accompanying drawings, Fig. 1 is an elevation of a clothes rack constructed in accordance with the principles of this invention; Fig. 2 is a section taken on the line 2—2 of Fig. 1; Fig. 3 is a top view; Figs. 4 and 5 are detail views of the fastening means.

In hotels, clubs, or wherever coat racks of this kind are used, one of the greatest objections to the ordinary or solid type of rack is that it occupies too much space when not in use, it is bulky, cumbersome, and hard to move. The present invention is not for a foldable rack nor one that is collapsible in this sense; the pieces are actually taken apart and to do this the cross pieces are simply raised or disengaged from the ends. The pieces can then be placed together or handled separately. When in knock-down form the storage space required is so much less that from eight to ten or more racks can be disposed in the same space occupied by one in its assembled condition.

Referring more particularly to the drawings, there are two end pieces 2 and 3, a top piece 4, a bottom piece 5, and an intermediate cross piece 6.

At the inner side of the end pieces 2 and 3 are double hook supporting members 7 each comprising an angular member of which one portion is secured to the end pieces, and the other portion extends inwardly therefrom and is formed with upper and lower hook notches 8 and 9. Each of the cross members 5 and 6 is provided at its end with spaced projections 10 preferably consisting of headed bolts, which are adapted to engage in the notches 8 and 9 of the double hook members 7. The cross

members 5 and 6 are therefore simply engaged or disengaged from the end pieces 2 and 3 by engaging or disengaging the projections 10 from the hook members, and no tools or special implements are required either for assembling or taking them apart. The projections are simply set into the tops of the notches and as the notches are bevelled outwardly, the cross pieces will move downwardly until the end of the cross pieces engages the rack end, or until the projections 10 reach the bottom of the notch. As the ends of the cross pieces are usually squared they will hold the frame in a rigid rectangular position.

The top member 4 is preferably formed with strips 11 spaced apart by blocks 12 disposed at intervals. At the ends on the underside are moulding strips 13 spaced apart to receive the upper extremities of the rack ends 2 and 3 therebetween so that the rack will be strengthened and steadied thereby and the top 4 will be held firmly in position. At the bottom of each end there is usually a foot piece 14 which extends somewhat beyond the side to afford additional stability to the rack.

The cross member 6 is provided on one or both sides with a plurality of hooks 15 and a hat supporting shelf 16 is attached to the top of the cross piece proper and is preferably of the same open or sectional construction as the top 4, as clearly shown by Fig. 3. This construction has the advantage that it is both light and strong. The ends may also be formed with cut out portions 17, as shown in Fig. 2 to make the rack more attractive and lighter.

With this construction it is obvious that the parts may be easily taken apart and assembled; they are easily handled, in carrying or packing them away; and a minimum space will be occupied in the knock-down form. Although the rack is shown as being made of wood or similar material, it is obvious that practically the same construction may be employed in making it of sheet metal. Other changes may be made without departing from the spirit and scope of the invention.

I claim:

1. In a knock-down clothes rack, an upright horizontal cross piece with clothes hooks on opposite sides, a hat shelf at the top of the cross piece projecting over the hooks, a pair of upright ends, and means

comprising spaced upwardly opening hooks projecting inwardly from each end and correspondingly spaced projections at the ends of the cross piece for detachably engaging the hooks.

2. In a knock-down clothes rack, an upper and lower horizontal cross piece in a vertical plane, clothes hooks on opposite sides of the upper cross piece, a hat shelf at the top 10 of the upper cross piece forming with it a cross brace T shaped in section, a pair of upright ends, a top piece with mouldings at the ends spaced to engage the upper extremities of the ends therebetween, and means for 15 detachably connecting the ends to the cross pieces, said means comprising a pair of spaced hooks and correspondingly spaced projections at each end of each of the cross pieces.

- 20 3. In a knock-down clothes rack of the class described, a pair of spaced ends, a top

having means on the underside at each end thereof for engaging both sides of the upper extremity of each of the ends, a bottom cross piece, a top cross member comprising a vertical cross piece and a horizontal hat shelf attached at the upper edge thereof, clothes hooks projecting from opposite sides of the top cross member, a pair of projections at each end of each of the cross pieces one above 25 the other, and double hook members attached to the inner side of each rack end, each hook member comprising an angular portion secured to the rack end and an angular portion projecting therefrom with hook notches 30 one over the other to engage the said projections, each notch being bevelled outwardly to receive the projection freely therein, and the end of the cross piece abutting the inner face of the frame end.

HENRY D. OBERDORFER.
